UPPER AND FOXING PRESSING MACHINE

Edward A. Willey, Malden, Mass., assignor, by
mesne assignments, to United States Rubber
Company, New York, N. Y., a corporation of
New Jersey

Application August 27, 1930, Serial No. 478,015

5 Claims. (Cl. 18—2)

My present invention relates to upper and foxing pressing machines and more particularly to an improved upper and foxing pressing machine for simultaneously pressing the foxing and 5 complete upper of gum rubber shoes, and also the cap portions of composite rubber and fabric footwear.

In the manufacture of rubber footwear, one of the most difficult operations to perform is the 10 uniform pressing of the component parts in such a manner as will cause the complete consolidation of all of the elements that make up the shoe. Particularly is this true with regard to the foxing, and the pressing of the foxing as well as the 15 pressing of the other portions of the shoe has heretofore been done manually and by means of a hand roller. With hand rolling, it is practically impossible for the operator to follow the irregular curves of the last and apply even pressure throughout the entire area of the shoe and the result has been that the various elements do 20 not entirely adhere and this lack of adherence results in the formation of air pockets. These air pockets produce blistered and weakened places 25 after the shoes are vulcanized and the parts at the blistered places separate when the shoe is flexed.

In my present invention, I have obviated the 30 difficulties heretofore experienced in this class of work and have devised a new and improved foxing and upper pressing machine in which all parts of the shoe operated on are subjected to an absolutely uniform pressure and the pressure may be as great as desired, the result being that 35 the elements constituting the shoe structure are completely consolidated. Air bubbles are prevented and separation of portions of the shoe structure from each other is prevented.

The principal object of the invention, therefore, 40 is an improved foxing and upper pressing machine.

Another object of the invention is an improved 45 automatic pressing machine controlled by fluid pressure.

A still further object of the invention is an 50 improved flexible enclosing bag for applying the pressure and which bag will conform with the contour of the various size lasts when under the required pressure.

55 In the accompanying drawings illustrating a preferred embodiment of our invention:

Figure 1 is a side elevation;

Fig. 2 is a front elevation;

Fig. 3 is an enlarged sectional detail of the last- 55 holding means;

Fig. 4 is a sectional detail showing the cover and safety mechanism associated therewith;

Fig. 5 is a central longitudinal section through one of the pressing cavities showing a shoe in position therein before pressure is applied there- 5 to;

Fig. 6 is a detail showing the fluid inlet safety mechanism;

Fig. 7 is a transverse section through the pressing cavities illustrating the pressure bag under 10 pressure;

Fig. 8 is a section through a portion of the gum rubber pressure bag showing the method of construction;

Fig. 9 is a detail of the one-revolution clutch; 15

Fig. 10 is a sectional detail of the spring housing for the cover-control means;

Fig. 11 is a fragmentary plan view of a portion 20 of the cover;

Fig. 12 is a detail of the one-revolution clutch throw-out cam, and 25

Fig. 13 is a detail showing the operating mechanism for the intake valve.

Reference to the drawing 10 designates a base 25 and secured to, or formed integral therewith, and at each corner thereof are upwardly extending standards 11 and mounted on the top of the standards is a platen 12. On an extension at one side of the base 10 is mounted a motor 13, the drive shaft 14 of which is connected to the drive shaft 15 of a speed reducing device 16, this speed reducing device being secured to the base 10 by bolts 17. The driven shaft 18 of the speed reducing device 16 has secured at one end thereof a member 19 of a one-revolution clutch. 30

The shaft 18 of the speed reducing device 16 is in alignment with a counter shaft 20 rotatably mounted in bearings 21 formed at the top of bearing standards 22, these bearing standards being secured to the top face of the base 10 in 35 any suitable manner. Keyed to, but slideable longitudinally of the counter shaft 20 is a one-revolution clutch member 23, this member being provided with a circumferential groove 24. Secured to the base 10 by bolts 25 is a bracket 26 and formed at the upper end of this bracket is a bearing at which is rotatably mounted a shaft 27. Secured at the inner end of the shaft 27 is a lever 28, at the upper free end of which is 40 rotatably mounted a roller 29 that engages in the circumferential grooves 24 in the one-revolution clutch member 23. Secured to the end of the shaft 27 remote from the lever 28 is a lever 30 and pivotally attached to the free-end of this lever 30 is one end of a connecting rod 45

the circumferential grooves 24 in the one-revolution clutch member 23. Secured to the end of the shaft 27 remote from the lever 28 is a lever 30 and pivotally attached to the free-end of this lever 30 is one end of a connecting rod 50 . 55

31. The other end of this connecting rod is pivotally attached to a lever 32 secured to one end of a shaft 33 which is rotatably mounted in a bearing 34 formed integral with one of the standards 11. Secured to the shaft 33 at the end thereof remote from the lever 32 is an operating lever 34 and by means of which the shaft 33 may be rotated. It will be obvious from an inspection of Fig. 2 that manipulation of the lever 34 will cause a movement of the sliding clutch member 23 into and out of engagement with the cooperating clutch member 19 and in the position shown in Fig. 2, the members 19 and 23 are out of engagement with each other, and, therefore, no motion is transmitted to the counter shaft 20.

Secured to the clutch member 23 by screw 35 and rotatable on such screw is a roller 36. Secured to the base 10 by bolt 37 is a holding standard 38 provided with a vertical slot 39 communicating with the hollow interior of the standard. Mounted for vertical reciprocation in the hollow standard 38 is a shaft 40, the lower end of which is hollow as indicated at 41 to provide housing for a compression spring 42, which tends to move the shaft 40 into its uppermost position. Formed integral with the shaft 40 and at the upper end thereof is an enlargement 44 that has formed thereon a cam 45 which cam is adapted to engage the roller 36 carried by the clutch member 23, and, as the clutch member 23 rotates, the same will be moved to the left, as shown in Fig. 9, on engagement with the cam 45 by the roller 36 to thus move the clutch member 23 out of engagement with the clutch member 19 and to move the same into position as shown in Fig. 9.

Extending through the vertical slot 39 and screwing into the shaft 40 is a stud 46. The end of the stud 46 is engaged by an elongated slot in a lever 47. This lever is attached at its other end to a shaft 48 journaled in a bearing 49 formed on one of the standards 11. At the end of the shaft 48 remote from the lever 47 is attached an operating lever 50. As constructed, it is necessary to operate both of the levers 34 and 50 to control the one-revolution clutch just described. Such detailed construction, however, is not necessary, but has been adopted for the sake of safety in order to prevent injury to the operator from other parts of the machine to be hereinafter described. In order to operate the machine therefore, as described, the operator must utilize both hands and, therefore, accidental injury is prevented. To operate the one-revolution clutch, the operator will manipulate the lever 50 to move the shaft 40 downwardly against the tension of the spring 42, thus moving the cam 45 out of engagement with the roller 36 on the clutch member 23. The lever 34 is then manipulated to rotate the shaft 33 and through the linkage 32, 31, 30 and 28 slides the member 23 into engagement with the member 19. The lever 50 and the lever 34 may now be released and power is transmitted to the counter shaft 20 from the shaft 18. As the counter shaft 20 completes a single revolution, the roller 36 thereon will be engaged by the cam 45 which has been moved up into position by the release of the lever 50 and the clutch member 23 is moved out of engagement with the clutch member 19.

The platen 12 is hollow and open on the bottom and on the top surface is formed parallelly arranged dovetailed portions 51. 52 designates pressure cavities or casings, the bases 53 thereof being beveled to engage with the beveled or dove-

tailed members 51 and are held in position on the platen 12 by a wedge shaped member 54 secured to the platen 12 by bolt 55, nut 56 and hand nut 57. In the drawings two of the pressure cavities 52 are shown, but any number of pressure cavities may be employed. Secured to the rear face of the platen 12 in any suitable manner is a bracket 58, at the upper end of which is formed aligned bearings 59 and in these bearings is rotatably mounted a shaft 60. Extending upwardly and forwardly from the shaft 60 is a cover holder 61. Formed integral with the member 61 and extending forwardly therefrom is an arm 62 and the free end of this arm is pivotally attached to the upper end of an adjustable connecting rod 63. The lower end of the connecting rod 63 is pivotally attached to a lever 64 and this lever at its other end is provided with a shaft 65 rotatably mounted in bearings formed in a bracket 66 attached to the under face of the platen 12. Intermediate the ends of the lever 64 is a cam roller 166 adapted to engage in a cam race 167 formed in one face of a cam 168 that is secured to the counter shaft 20 and as the counter shaft 20 rotates, the upper and forward end of the member 61 is moved toward and from the upper open end of the pressure cavities 52, as will be hereinafter described.

Referring to Fig. 5, it will be noted that the interior of the pressure cavities 52 is approximately the shape of a boot or shoe 67, but is larger than such boot or shoe and of interior dimensions sufficient to accommodate several different sizes thereof. Fitting within the interior of each of the pressure cavities 52 is a pressure diaphragm 68 which normally is in relatively close engagement with the interior walls of the cavity. The upper end or edge of the pressure diaphragm 68 is provided with an accordion plait 69 and the peripheral edge extends over an upwardly projecting lip 70 of the pressure cavities 52 and is held firmly in position by a compression ring 71 secured to the pressure cavity 52 by a plurality of bolts 72. When in normal position, or the position shown in Fig. 5, the upper edge of the accordion plait 69 of the pressure diaphragm 68 lies below the upper surface of the compression ring 71, and within the compression ring 71 is adapted to fit the peripheral edge of the actual cover 73.

Resting within the cavity formed in the pressure cavity 52 and against the surface of the diaphragm 68 is an insert 68^a of relatively thick resilient material, such as soft or sponge rubber, and as will be noted from inspection of Fig. 5, the boot or shoe 67 rests on the surface of such insert 68^a. It is desirable that the diaphragm 68 be resilient, but practically inextensible and to accomplish this, I preferably make such diaphragm as indicated in Fig. 8 where it will be noted that such diaphragm is composed of a relatively thick layer of rubber 150, a relatively thin layer of rubber 151 and a layer of fabric 152 interposed therebetween. As fluid under pressure is admitted to the pressure cavity 52 through the pipe 115, the diaphragm 68 will first move into engagement with the cover 73 and the soft or sponge rubber insert 68^a will adapt itself readily to the contour and indentations of the boot or shoe 67. Also this soft or sponge rubber 68^a will lend itself readily to the distortion that is created when it has to conform itself to lasts of different style and size. As the pressure within the pressure cavity 52 is increased, the diaphragm 68 and insert 68^a will assume the form shown in Fig. 7.

Secured to the underface of the cover-holding

member 61 by bolts 74 are covers 73, while mounted on and extending through the cover-holding member 61 are heel and sole engaging and positioning members to be hereinafter described. The covers 73 are cut away to allow passage of such members therethrough. Both the heel and sole engaging and positioning members are substantially identical in construction and operation, although the mounting thereof is different, but reference is made to Fig. 3 for a general disclosure thereof. The mounting consists essentially of a cylindrical member 75 in which is slidably mounted a shaft 76 having a pivotally mounted shoe or spud 77 at its lower end and which is adapted to engage with the heel or the sole of the boot or shoe 67. Extending upwardly from the member 76 is a reduced portion 78 provided with a head 79 and between the head and the upper surface of the member 75 is arranged a coil spring 80 and a washer 81, the spring 80 always tending to lift the member 76 into its uppermost position. One side of the member 76 is provided with a ratchet 82 adapted to be engaged by a spring pressed pawl 83 and which pawl is adapted to hold the member 76 in its downwardly adjusted position. Associated with the spring pressed pawl 83 is a pawl release lever 84 which may be operated to move the pawl 83 out of engagement with the ratchet 82 and allow the spring 80 to function in the usual manner.

Ordinarily the heel of the boot or shoe 67 to be operated on will come into substantially the same position in the interior of the pressure cavity 52, but due to variations in the size of such boot or shoe, it is necessary to provide adjustment for the sole stop employed. The method of adjustment is illustrated in Fig. 11 where it will be noted that the cover holding member 61 is provided with an elongated slot 85 and on each edge of this slot is secured a guide plate 86 and on the guide plates 86 is slidably mounted a carrier member 87 for the cylindrical member 75. On the cover holding member 61 and adjacent to one of the guiding plates 86 is secured a rack 88 adapted to be engaged with a member 89 associated with the carrier 87. By adjusting the member 89 with respect to the rack 88, the position of the carrier 87 in the slot 85 may be varied at will and the character of the rack 88 and associated member 89 is such that the carrier 87 will be retained against ordinary pressure in the position in which it may have been placed.

In operation, the boot or shoe 67 is placed in the pressure cavity 52. The cover-holding member 61 is rotated above the shaft 60 until the cover 73 fits into the opening in the compression ring 71 and the operator presses on the portion 79 of the part 78 to force the members 76 downwardly until the members 77 engage with the sole and heel of the boot. This setting is then sufficient for the particular size boot or shoe 67 being worked upon and until the size of the boot or shoe being worked upon is changed, no further adjustment of the parts referred to is necessary.

As the counter shaft 20 rotates, a swinging movement is imparted at stated intervals to the cover-holding member 61 and the forward movement is extremely rapid. In order to prevent shock to such swinging member 61 and the parts carried thereby, I have associated therewith the following device. 90 designates a lever arm formed integral with and extending outward from the member 61 and the outer free end of this lever arm is pivotally attached at 91 to the upper end of a piston rod 92. This piston rod is slidably

mounted within a cylinder 93 pivotally attached at 94 to a bracket 95 on the top of the base 10. The lower end of the piston rod 92 is threaded to receive a nut 96 which holds a washer 97 on the piston rod. Surrounding the piston rod 92 and with its lower end in engagement with the upper face of the washer 97 is a spring 98. The upper end of the cylinder 93 is threaded to receive an adjusting sleeve 99, the piston rod 92 passing through such sleeve. On the outer threaded portion of the sleeve 99 and engaging with the extreme upper end of the cylinder 93 is a lock nut 100 and by means of which the sleeve 99 may be held in adjusted position. The underface of the sleeve 99 engages with the upper end of the spring 98 and the mechanism just described is the means for adjusting the tension of the spring 98. As the counter shaft 20 rotates and the cover member 61 rotates in a counter-clockwise direction by the cam on the counter shaft, any tendency to pound on the part of the member 61 is prevented by the cushioning effect of the spring 98 so that as the cover 73 is brought into its position with respect to the compression rings 62, the member 61 is practically at rest.

On opposite sides of the cover member 61 are formed recesses 101 to allow passage of the upper end of the locking members 102. The locking members engage surfaces 103 on either side of the passage 101. Formed on the under side of 30 the platen 12 and at opposite sides thereof are aligned bearings 104 in which bearings is rotatably mounted a shaft 105. Secured to such shaft and at each end thereof is a gear sector 106 for a purpose to be hereinafter described. Secured to the shaft 105 intermediate its ends and extending radially outward therefrom is an arm or lever 107. The outer free end of this arm is provided with a rotatable cam roller 108 adapted to be engaged by a cam race 109 in a cam plate 40 110 that is attached to the counter shaft 20.

Secured to the opposite ends of the platen 12 by bolts 111 are vertically extending bearing members 112 and in each of these bearing members is rotatably mounted one of the locking members 102. Secured to the lower end of each of the locking members 102 is a pinion 113; this pinion meshing with and driven by the gear sector 106. At the upper end of the locking members 102 are formed T heads 114, these T heads engaging with the surfaces 103 on the cover-holding member 61.

The cam member 110 is so located on the counter shaft 20 that the cam race 109 therein will operate to control the lever 107 to cause a rotation of the locking members 102 only after the cam member 68 has caused the cover-holding member 61 to bring the cover 73 into proper position with respect to the compression ring 71 and to also cause a reverse rotation of the locking members 102 so as to release the cover holding member 61 at the proper point during the cycle of operations which will be hereinafter described.

In order to positively insure that the locking members 102 will not be rotated until the cover-carrying member 61 is in its lowermost position, I have attached to one of the locking members 102, a member 120 in a cavity 121 in the bearing member bracket 112 and in this member 120 I 65 arrange a vertically movable spring-pressed plunger 122. In the unlocked position of the locking members 102, the upper end of the spring-pressed plunger 122 engaging in the lower end of a vertical hole 123 in the bearing member 112. 70 75

Also freely slideable in the hole 123 is a plunger 124, the upper end of which lies in the path of movement of spring-pressed plunger 124' carried by the cover holding member 61. The cover holding member 61 in its movement to closing position brings the spring-pressed plunger 124' carried thereby into engagement with the top end of the plunger 124 and when the cover holding member 61 is in its lowermost position, the lower end of the plunger 124 will be engaged with the upper end of the spring pressed plunger 122 and will have moved the same out of engagement with the lower end of the hole 123. When this occurs, it will be possible to rotate the locking members 102 and move the locking members 114 thereon into engagement with the surface 103 above described. Each of the pressure cavities 52 is connected by pipes 115 and 116 to a pipe 117 leading to any suitable source of fluid supply under pressure and interposed between the pipe 117 and pipes 116 is an inlet valve 118. Connected to the pipes 116 is an exhaust valve 119. Forming a part of the inlet valve 118 is a valve stem 125. Secured to the bottom of the platen 12 is a bracket member 126 in which is rotatably mounted a shaft 127. Rotatably mounted on the shaft 127 and extending rearwardly of the machine is a lever 128, and the rear end of such lever has rotatably mounted thereon a cam roller 129. The cam roller 129 engages with a cam comprising relatively movable elements 129' and 130. These elements 129' and 130 are adjustable with respect to each other in order to vary the time of operation of the inlet valve 118 and the two elements 129' and 130 are held in adjusted position by bolts 131. Pivottally mounted on the lever 128 is a member 132, the upper end of which is adapted to engage with the lower end of the valve stem 125. Also forming part of the element 132 is a cylindrical member 133 adapted to be rotated between the jaws of a forked member 134. This forked member 134 is secured to one end of a shaft 135 that is slidably mounted in suitable bearings on the other side of the platen 12. Adjacent the end of the sliding shaft 135, remote from the forked member 134 are spaced blocks 136. Secured to the lower extended end of the adjacent member 102 by pin or screw 137 is a collar 138 and extending upwardly from such collar 138 is a pin 139 arranged to be brought into engagement with one or the other of the blocks 136. This construction not only insures operation of the inlet valve 118, but also insures that such valve will only be operated at the right time. The locking member 102, as above described, can only operate when the cover carrying member 61 is in its lowermost position and the rotation of the locking member 102 will move the sliding shaft 135 in such a direction as to have the forked member 134 move the member 132 mounted on the lever 128 into operative position beneath the valve stem 125. The cam roller 129 on the lever 128 will rotate the lever on the shaft 127 and bring the member 132 into engagement with the valve stem 125 to operate the valve 118. As the countershaft 20 rotates this rotation together with the cam 129 determines the length of time the fluid is allowed to flow through the pipe 117 and pipes 116 into the pressure cavities 52, after which the valve 118 is closed.

Secured to the bottom of the platen 12 in any suitable manner is a bearing bracket 140 and secured to such bracket is a shaft 141. Rotatably mounted on the shaft 141 is a lever 142 carrying

at its free end a cam roller 143. This cam roller engages with a cam 144 secured to the counter shaft 20. The upper face of the lever 142 is adapted to be brought into engagement periodically with the valve stem 145 of the exhaust valve 119. It will be understood of course that the cam elements 129'—130 and the cam 144 are so arranged with respect to each other on the counter shaft 20 that the inlet and exhaust valve 118 and 119, respectively, will not open at the same instant, that is the cams are so arranged that the inlet valve is opened at the proper time and for the proper length of time in the cycle of operations and also the exhaust valve 119 is operated at the proper time to reduce or exhaust the pressure from within the pressure cavities.

The operation of the machine is as follows: The operator places the unvulcanized lasted boot or shoe 67 within the pressure cavity 52 and against the surface of the rubber insert 68a, as clearly shown in Fig. 5. It will be assumed that the heel and sole positioning elements 77 have been adjusted for the size and shape of shoe to be operated upon. The operator will now move the lever 50 so as to release the throw-out cam 56 from the roller 36 and will then operate the lever 34 to move the clutch element 23 into engagement with the clutch element 19. The motor 13 being in operation, power will be transmitted to the counter shaft 20. Cam 168 will operate the lever 64, so as to rotate the covering holding member 61 in a counter-clockwise direction as viewed in Fig. 1, and will move the cover 73 downward into the position indicated in Fig. 5. As this occurs the spring pressed plunger 124' moves the plunger 124 downwardly so as to release the spring pressed plunger 122 carried by the member 120 permitting the lever 107 to be operated by the cam 110 to move the gear segments 106 so as to rotate the locking members 102 and bring the members 114 thereon into engagement with the surfaces 103, thus locking the cover 73 and cover holding member 61 in proper position. This rotation of the locking members 102, brought the pin 139 carried by one of such members into engagement with one of the blocks 136 and rotated the member 132 into operative position with relation to the valve stem 125. Further continued rotation of the countershaft 20 will cause the cam elements 129' and 130 to move the lever 132 into position to operate the inlet valve 118 and fluid under pressure passes from the pipe 117 through the pipe 115 and into the pressure cavities 52. As the pressure builds up within the cavity, the diaphragm 68 and the insert 68a assume the position shown in Fig. 7 and pressure is applied to all parts of the boot or shoe 67 simultaneously and equally.

As the counter shaft 20 continues its rotation the cam 144 will control the lever 142 to operate the exhaust valve 119 relieving the pressure within the pressure cavities 52 and allowing the diaphragm 68 and insert 68a to reassume the position shown in Fig. 5. The cam 110 will now operate to rotate the shaft 105 thus rotating the locking members 102 and releasing the members 114 thereon from the surfaces 103. The continued rotation of the counter shaft 120 will now cause the cam 168, by the medium of the lever 64, to move the cover-holding member 61 in a clockwise direction until it assumes the position shown in Fig. 1. After this occurs, the roller 36 on the clutch member 23 will engage with the cam 45 and said clutch member will move out of engagement with the clutch member 19 and all parts of

the machine will be brought to rest preparatory to going through another cycle of operations on another boot or shoe 67.

Having thus described my invention what I claim and desire to protect by Letters Patent is:

- 5 1. An improved foxing and upper pressing machine, comprising a pressure casing, a diaphragm, normally occupying a position against the walls of the casing, a sponge rubber insert in engagement with the diaphragm and extending over the major portion thereof, said diaphragm and insert forming a recess for a boot or shoe in process of manufacture, sole and heel engaging stops for holding the boot or shoe in position in the recess, and means for applying fluid pressure to the pressure casing to force the diaphragm and insert into intimate engagement with the entire upper and a predetermined portion of the outsole of the boot or shoe.
- 10 2. An improved foxing and upper pressing machine, comprising a pressure casing, a diaphragm and a sponge rubber insert in engagement with each other and normally occupying a position against the walls of the casing, said diaphragm and insert forming a recess to receive an inverted boot or shoe in process of manufacture, means for engaging the bottom of the boot or shoe when in position in the recess, and means for applying fluid pressure to the pressure casing to force the insert into intimate engagement with the entire upper and a predetermined portion of the outsole of the boot or shoe.
- 15 3. In an improved foxing and upper pressing machine, the combination of a casing having a recess formed therein of substantially the shape of a rubber boot or shoe, a diaphragm disposed therein and clamped at its edge to the open end of the recess, an elastic and compressible insert in engagement with the outer surface of the diaphragm, a plurality of heel and sole engaging
- 20 stops for maintaining the boot or shoe in relatively fixed position within the diaphragm and on the insert, means for supplying fluid under pressure to the recess to distend the diaphragm, whereby the elastic and compressible insert is forced against the entire upper and a predetermined portion of the bottom of the boot or shoe.
- 25 4. In an improved foxing and upper pressing machine, the combination of a casing having an approximately shoe shaped recess formed therein, a diaphragm having normally the contour of the walls of the recess, means for clamping the peripheral edge of the diaphragm adjacent to the open end of the recess, said diaphragm and recess forming a fluid pressure chamber, means for applying fluid under pressure to the chamber, a resilient and compressible insert in engagement with the outer surface of the diaphragm, and forming a bed on which may rest the top end of a last carrying a rubber boot or shoe in process of manufacture, stops for engaging with the bottom of a lasted boot or shoe for maintaining the same within the recess, said insert engaging with the entire upper and a predetermined portion of the bottom of the lasted boot or shoe upon the application of fluid under pressure to the pressure chamber.
- 30 5. In a footwear pressing machine, a pressure casing having therein a flexible diaphragm, a movable closure for the casing provided with adjustable means for engaging a footwear article disposed within the casing, locking means for maintaining said closure in closed position, a stop for preventing actuation of said locking means, and means for successively actuating said closure, releasing said stop, actuating said locking means, and applying fluid under pressure to said diaphragm to press a footwear article.

EDWARD A. WILLEY. 40
